(57) **CLAIM**

I claim the ornamental design for a protective cover for electronic game device, as shown and described.

DESCRIPTION

FIG. 1 is a front perspective view of a protective cover for electronic game device showing my new design;

FIG. 2 is a front elevational view of the protective cover of FIG. 1;

FIG. 3 is a rear elevational view of the protective cover of FIG. 1;

FIG. 4 is a left side elevational view of the protective cover of FIG. 1;

FIG. 5 is a right side elevational view of the protective cover of FIG. 1;

FIG. 6 is a top plan view of the protective cover of FIG. 1; FIG. 7 is a bottom plan view of the protective cover of FIG. 1;

FIG. 8 is a first front perspective view of a upper cover of the protective cover of FIG. 1;

FIG. 9 is a front elevational view of the upper cover of FIG. 8;

FIG. 10 is a rear elevational view of the upper cover of FIG. 8;

FIG. 11 is a left side elevational view of the upper cover of FIG. 8;

FIG. 12 is a right side elevational view of the upper cover of FIG. 8;

FIG. 13 is a top plan view of the upper cover of FIG. 8; FIG. 14 is a bottom plan view of the upper cover of FIG. 8; FIG. 15 is a second front perspective view of the upper cover of FIG. 8;

FIG. 16 is a front perspective view of a bottom cover of the protective cover of FIG. 1;

FIG. 17 is a front elevational view of the bottom cover of FIG. 16;

FIG. 18 is a rear elevational view of the bottom cover of FIG. 16;

FIG. 19 is a left side elevational view of the bottom cover of FIG. 16;

FIG. 20 is a right side elevational view of the bottom cover of FIG. 16;

FIG. 21 is a top plan view of the bottom cover of FIG. 16; FIG. 22 is a bottom plan view of the bottom cover of FIG. 16;

FIG. 23 is a front perspective view showing the upper cover of FIG. 8 separated from the bottom cover of FIG. 16;

FIG. 24 is a rear perspective view showing the upper cover of FIG. 8 and the bottom cover of FIG. 16 in a combination; and,

(Continued)

FIG. 25 is a front perspective view showing the upper cover of FIG. 8 and the bottom cover of FIG. 16 in use. The broken lines in the drawings depict portions of the protective cover for electronic game device that form no part of the claimed design. The broken lines and unshaded regions bounded by broken lines form no part of the claimed design.
